UNITED STATES PATENT OFFICE.

SAMUEL G. BRIGEL, OF PITTSBURGH, PENNSYLVANIA, ASSIGNOR TO JOHN M. HAVERTY, TRUSTEE, OF PITTSBURGH, PENNSYLVANIA.

METHOD AND APPARATUS FOR PRODUCING A COMBUSTIBLE MIXTURE.

1,346,935.

Specification of Letters Patent.

Patented July 20, 1920.

Application filed September 24, 1919. Serial No. 326,050.

To all whom it may concern:

Be it known that I, SAMUEL G. BRIGEL, residing at Pittsburgh, in the county of Allegheny and State of Pennsylvania, a citizen of the United States, have invented or discovered certain new and useful Improvements in Methods and Apparatus for Producing a Combustible Mixture, of which improvements the following is a specification.

The invention described herein relates to certain improvements in gas burners. It has heretofore been the practice to so construct burners that the jet or stream of gas is surrounded by an annular stream of air, the quantity of air admitted being proportional to the quantity of gas, but as the gas is lighter than the air, it would move upwardly and commingle with the air of the upper portions of the annular stream of air, and the lower portions of such annular stream would flow along under the stream of gas without mixing therewith, and hence when the quantity of air is so proportioned to the quantity of gas that only the amount of air required for the combustion of the gas is admitted, part of the air will not be utilized for combustion, but passes into the furnace without producing any beneficial effect, and by reason of this loss of air a full complete combustion of the gas is not obtained.

The object of the invention described herein is to provide for directing a thin stream or sheet of gas below a sheet or flat stream of air entering the mixing chamber at a point or points above the gas inlet so that a mixing of the gas and air may result primarily through the difference of the specific gravities of the two, as the gas being of less specific gravity than the air will rise up and the air will move down, thus insuring a thorough commingling of the gas and air. The invention is hereinafter more fully described and claimed.

In the accompanying drawing forming a part of this specification, Figure 1 is a top plan view of a burner embodying my improvements; Fig. 2 is a sectional elevation of the same, and Figs. 3 and 4 are views similar to Figs. 1 and 2 and illustrate a modification of the burner.

In the practice of the invention it is preferred to introduce the gas into a receiver 55 or gas chamber 1 which is preferably pro-

vided with inlets 2 on both upper and lower faces to facilitate connection with supply pipes. Gas flows from this chamber through a narrow slit 3 into a mixing chamber 4 which is preferably made independent 60 of the gas chamber, and bolted thereto. The gas chamber is preferably provided on one side with a nose-like extension 5, which projects into the open rear end of the mixing chamber, said nose resting on the under wall of the mixing chamber. The inlet slit is formed in the end of the nose so that gas issuing therefrom will flow in a wide thin sheet closely adjacent to the lower inner surface of the chamber toward the outlet of the chamber. The gas discharge 3 is so constructed that the gas delivered into the mixing chamber will flow through the chamber as a thin stream having a width equal or approximately equal to the internal width of said chamber, and to this end the discharge from the gas chamber may be formed by one or more narrow slits or by a plurality of closely adjacent small perforations.

The air for supporting combustion enters the mixing chamber through a port or ports so constructed and arranged that the air will flow into and along the chamber in the form of a stream having a width substantially equal to that of the gas. This stream of air as it enters the chamber is preferably directed downward toward the stream of gas and forwardly toward the outlet from the mixing chamber, so that it will 90 impinge on the stream of gas at an acute angle.

As the gas enters the mixing chamber it will tend to move upwardly and encounter and mix (to a greater or less degree) with the downwardly and forwardly flowing stream of air. The mixing of the air and gas will not be complete where they first come into contact, and hence there will be a stream of gas and a stream of air flowing 100 forwardly from the point or line of initial contact, but as the gas is lighter than the air, they will mingle more and more as they approach the outlet from the mixing chamber.

In practice, the gas will be supplied to the mixing chamber, at a low pressure, *e. g.*, an inch and one-half (1½") to two inches (2") water column, more or less, and the mixing chamber is made of such a size that

the flow of gas will be affected more by the stack draft in the fire box than the pressure in the gas chamber. As the rate of flow of gas will be due almost entirely to stack draft, its movement will have little or no effect on the rate of flow of the air, and hence the rate of flow of the latter will also be due to stack draft. As the flow of both the gas and air is due to the same cause, 10 their rate of flow will be substantially equal and there will not be any such difference in rates of flow as would retard their commingling due to differences in specific gravity. The mixing chambers are made of 15 such a length relative to the rate of flow of the gas and air as to permit of a thorough commingling of the gas and air before escaping from the mixing chamber.

It will be preferable in most cases to admit air at different points into the portion 20 of the mixing chamber above the plane of flow of the gas and to that end a series of suitably spaced ports 6 are formed in the top wall of the mixing chamber, the flow 25 of air through said ports being controlled by a valve 7 which can be shifted by any suitable means, as for example, by a lever 8 as shown. As shown, one of the air inlet ports is so located that the inflowing gas 30 will encounter the air at about the time the gas enters the mixing chamber, and when only one air inlet port is employed, as shown in Figs. 3 and 4, it is arranged to permit of the early contact of the air and 35 gas.

While not necessary, provision may be made for crowding together the streams of gas and air by causing a convergence of the upper and lower walls of the mixing 40 chamber, as indicated at 9 and 10, Fig. 2.

I claim herein as my invention:

1. The method of producing a combustible mixture of air and gas lighter than air which consists in directing a stream of gas lighter 45 than air and having a width greater than its thickness through a suitable chamber, and directing a quantity of air sufficient to effect substantially complete combustion of the gas into the chamber in the form of a stream 50 having a width approximately equal to that of gas at a point above the stream of gas, and in such relation thereto that a completely combustible mixture of the gas and air would be effected by reason of the relative specific gravities of the gas and air.

2. The method herein described of producing a combustible mixture of air and gas lighter than air, which consists in directing a stream of gas having a width greater than 60 its thickness through a suitable chamber, and so directing a stream of air of approximately the same width on to the upper surface only of the stream of gas, and causing such streams to flow at substantially the same rate 65 through said chamber.

3. The method herein described of producing a combustible mixture of air and gas lighter than air, which consists in directing a stream of gas along the bottom of a suitable chamber, and directing a quantity of air sufficient to effect substantially complete combustion in the form of a stream into the space between the upper surface of the stream of gas and the top of the chamber, thereby affording opportunity for opposite 70 vertical movements of the fluids of the two streams.

4. The method herein described of producing a combustible mixture of air and a gas lighter than air which consists in directing 80 a stream of such gas having a width greater than its thickness along the bottom of a suitable chamber and directing a quantity of air sufficient to effect substantially complete combustion of the gas in a plurality of 85 streams of substantially the same width into the space between the upper surface of the stream of gas and the top of the chamber.

5. In a burner for gas lighter than air the combination of a mixing chamber, means for introducing gas lighter than air into the mixing chamber in a direction parallel with the bottom of the chamber and an air inlet port arranged in a plane above the point of entrance of the gas thereby insuring a 95 thorough commingling of the fluids differing in specific gravity as they pass through the mixing chamber.

6. In a burner for gas lighter than air the combination of a mixing chamber, means 100 for introducing gas lighter than air in the form of a stream having a width greater than its thickness in a direction parallel with the bottom of the chamber and an air inlet port arranged in a plane above the point of entrance of the gas thereby insuring a 105 thorough commingling of the fluids by reason of their different specific gravities as they pass through the mixing chamber.

7. In a burner for gas lighter than air the combination of a mixing chamber, means 110 for introducing gas lighter than air in the form of a stream having a width greater than its depth or thickness at a point a substantial distance below the top of the mixing chamber, and means for introducing a quantity of air sufficient to effect substantially complete combustion of the gas into the space intermediate the top of the mixing chamber and the stream of gas so that by 115 reason of their difference in specific gravity the two fluids will intermingle as they pass through the mixing chamber.

8. In a burner for gas lighter than air the combination of a mixing chamber, means 120 for introducing gas lighter than air in the form of a stream having a width greater than its thickness or depth in a direction parallel with and adjacent to the bottom of the chamber and a plurality of ports for the 125

admission of air into the chamber, all of said ports being so arranged as to direct the air for the substantially complete combustion of the gas into the chamber at points 5 above the stream of gas so that all fluids will intermingle by reason of the difference in specific gravity as they flow through the mixing chamber.

9. In a gas burner the combination of a 10 mixing chamber a gas chamber having a nose projecting into one end of the mixing chamber and having an outlet adapted to direct a stream of gas lighter than air and having a width greater than its depth or

thickness into the mixing chamber at a point 15 adjacent to the bottom of said chamber, said mixing chamber being provided with ports arranged to direct air for combustion into the chamber above the plane of flow of the gas through the mixing chamber whereby 20 the gas and air for combustion are free to mingle by reason of their difference in specific gravity, and means for regulating the flow of air into the mixing chamber.

In testimony whereof I have hereunto set 25 my hand.

SAMUEL G. BRIGEL.
